DESIGN FOR AN OPHTHALMIC MOUNTING

Edward M. Splaine, Southbridge, Mass., assignor
to American Optical Company, Southbridge,
Mass., a voluntary association of Massachusetts

Application October 26, 1936, Serial No. 65,515

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for an Ophthalmic Mounting, of which the following is a specification, reference being made to the accompanying drawing, forming a part thereof.

Fig. I is a front view of an ophthalmic mounting showing my new design;

Fig. II is a perspective view of the complete ophthalmic mounting; and

Fig. III is a plan view of Fig. I.

The temples have been omitted from Figs. I and III for convenience of illustration.

The dominating features of the design are shown in full lines in the drawing. The characteristic features of my design reside in the provision of temple supports so bent as to form portions which continue from the upper contour edges of the temples with a flow line which blends with the upper contours of the temporal portions of the lens rims, thus producing a balanced streamline effect at the upper temporal portions of the lens rims. The lower portions of the temporal supports each have a part extending forwardly from the ends of the temples to a point substantially in the plane of the lens rims and thence curve downwardly with a quick bend

blending into said lens rims along a curved line.

The bridge member is formed of two separate bar-like members which are of relatively thin material curved rearwardly with one of said bar-like members lying above the other. The said rearwardly curved portions of the upper bar-like member turn forwardly and upwardly and blend into the upper contour portions of the lens rims on the nasal sides thereof, forming substantially triangular openings at the points of contact with the lens rims when viewed from the front of the spectacle frame. The said upper bar-like member is further provided centrally with an upwardly bent arched portion lying in spaced relation with the lower bar so as to produce small triangular openings centrally of the bridge member. The lower bar curves rearwardly with substantially the same line of curvature as the upper bar and is provided with portions turned downwardly and forwardly. The lens rims have their upper portions formed flatter in curvature than their lower portions so that the said upper portions blend with the upper temporal supports and bridge bar so as to produce a streamline effect.

I claim:

The ornamental design for an ophthalmic mounting substantially as shown and described.

EDWARD M. SPLAINE.
